FILING VISE FOR CIRCULAR SAWS

Elmer M. Black, Merriam, Kans.

Application February 8, 1954, Serial No. 28,909

Term of patent 7 years

(Cl. D37—1)

Fig. 1.

Fig. 2.

Fig. 3.

Fig. 4.

To all whom it may concern:

Be it known that I, Elmer M. Black, a citizen of the United States, residing at Merriam, in the county of Johnson and State of Kansas, have invented a new, original, and ornamental Design for a Filing Vise for Circular Saws, of which the following is a specification, reference being had to the accompanying drawing forming a part thereof, wherein:

Fig. 1 is a front elevational view of a filing vise for circular saws, showing my new design.

Fig. 2 is a side elevational view thereof.

Fig. 3 is a rear elevational view thereof; and

Fig. 4 is a top plan view of the filing vise for circular saws.

I claim:

The ornamental design for a filing vise for circular saws, as shown.
